SEPARABLE TOY FIGURE FOR A CONSTRUCTION GAME OR THE LIKE

William H. Schaper, Robbinsdale, Minn.

Application March 20, 1950, Serial No. 8,648

Term of patent 14 years

(Cl. D34—2)

To all whom it may concern:

Be it known that I, William H. Schaper, a citizen of the United States, resident of Robbinsdale, county of Hennepin, State of Minnesota, have invented a new, original, and ornamental Design for a Separable Toy Figure for a Construction Game or the like, of which the following is a specification, reference being had to the accompanying drawing, forming a part thereof.

Fig. 1 is a front perspective of a separable toy figure for a construction game or the like showing my new design;

Fig. 2 is a top plan view thereof; and
Fig. 3 is a side elevational view.

I claim:

The ornamental design for a separable toy figure for a construction game or the like, substantially as shown.

WILLIAM H. SCHAPER.
